ELECTROMAGNET FOR PRINTING
MACHINES AND THE LIKE

Frederick Shurley, Los Angeles, Calif.

Application May 6, 1931, Serial No. 535,396
Renewed March 10, 1934

2 Claims. (Cl. 175—367)

This invention relates to electro-magnets for printing machines, and the like, whereby metallic or metalized stencils are held and tightly pressed against a sheet of paper, cloth, glass, metal, etc., for the purpose of decorating, painting or cutting the same. The invention consists of a multi-polar electro-magnet which has at least one substantially plane surface of relatively large area.

- 10 An object of my invention is to provide an electro-magnet of the character stated in which the plane surface is composed of a number of alternate magnetic strips or surfaces of opposite polarity. In tables of this character heretofore in use, "cold spots" were present, over which the stencil was not firmly held. This is particularly undesirable where paint, enamel, or other liquid substances are applied by spraying thru a stencil opening. A raised portion or edge of the stencil 20 will permit the liquid to pass under the stencil and will spoil the work.

Another object is to overcome these difficulties by providing an electro-magnet of the character stated which has a practically uniform attractive force over the entire surface of the magnet. I accomplish this by providing a multiplicity of regions of opposite magnetic polarity so that there is a magnetic field between the plus and minus regions. When magnetic material is brought near the table, it endeavors to share the flux carried thereby and the table and approaching material attract each other uniformly. The lines of force in my table are substantially perpendicular to the surface thereof and to the approaching stencil, and as previously stated, are practically uniform thruout the entire surface.

In the accompanying drawing and detailed description, I have presented my invention for use with a stencil which is sprayed or brushed upon to give the desired print upon a paper, cloth, metal or other surface. It is to be understood that the description and details of the particular embodiment of the invention illustrated in the drawing are given only by way of example to explain the nature and character of the invention, and are not to be construed as limiting the same short of its scope as expressed in the appended claims.

Other objects, advantages and features of invention may appear from the accompanying drawing, the subjoined detailed description and the appended claims.

In the drawing
Figure 1 is a fragmentary, top plan view of my electro-magnet.

Figure 2 is a transverse, sectional view of the same.

Figure 3 is an enlarged, fragmentary, sectional view taken on line 3—3 of Figure 2.

Figure 4 is a fragmentary, sectional view taken on line 4—4 of Fig. 2.

Figure 5 is a perspective view of a slightly modified form of magnet which forms the table.

Referring more particularly to the drawing, the numeral 1 indicates the metal base of my magnetic table, which is here shown as substantially rectangular in form, altho any other shape may be utilized if desired. A plurality of metal cores 2 rises from the base 1 and is suitably secured therein. In the present instance, the cores are secured by means of screws 3 which extend thru the base and into the end of the cores. The cores are equidistantly spaced over the entire surface of the base, the purpose of which will be evident as the description proceeds. A spool 4 formed of non-magnetic material surrounds each of the cores 2 and on each spool there is wound a coil of wire 5. By this means, an electro-magnet is formed with a magnetic core thru which the flux or lines of force are carried.

Above the electro-magnets, I position a solid plate 6 which is formed of a magnetic material. Spaced above the plate 6 and attached to the ends of each of the cores 2, there are magnetic plates 7 substantially rectangular in form in the present instance, and each of these plates is magnetized uniformly thruout the entire surface of the table so as to uniformly attract a stencil, or the like, for the purpose of printing, cutting or the like. There is an individual magnet plate 7 for each core 2. The plate 6 and the magnet plates 7 are separated by a layer of non-magnetic material 8, which material also extends between the various magnet plates to segregate these last named plates substantially as shown in Figures 1 and 3.

Intersecting grooves 9 are cut in the top surface of the magnet plates 7, and these grooves are filled with a non-magnetic material 10. The cores 2 extend thru and contact with the plate 6, and are suitably secured to the magnet plates 7. Thus, both of the members 6 and 7 are energized by the cores.

Electrical current from a suitable source is conducted to the wires 5 on each of the spools, and the spools may be connected in series or in parallel, whichever is found more desirable. A strip of insulating material 11 is provided above the spools 4 and a second strip of insulating material 12 is positioned below the spools. A casing 13 surrounds the magnetic table and is secured to the

base 1 and to the plate 6 by means of screws, or the like.

When an electrical current traverses the coils 5, strong magnetic attraction is evident in the magnetic plates 7, due to the conduction of the lines of force thereto thru the cores 2.

In Figure 5, I have shown a slightly modified form of magnet which may be built up to form a table for the same purpose as that previously described. In the present instance, a plurality of substantially Y-shaped metal plates 14 are placed side by side and are separated by Y-shaped strips of insulating material 15. The entire pack is surrounded by a coil of wires 16 thru which an electrical current is passed. The electrical current passing thru the coil magnetizes the metal plates. Strips 17 are secured adjacent the upper edge of the magnetic table and each strip is provided with a longitudinally extending groove 18 to which a tube 19 extends. A partial vacuum from a pump (not shown) is drawn in the tubes 19 and when a sheet of paper, cloth, leather, or the like is placed over the strips 17 and over the grooves therein, it will be drawn tightly against the surface of the magnetic table so that it can be acted upon thru a metal stencil which is placed over the paper, or the like. The metal stencil is drawn tightly against the sheet of cloth or the like by the pack of magnets.

Having described my invention, I claim:

1. An electro-magnet comprising a metal base, a plurality of spaced cores secured in said base and rising therefrom, a spool threaded on each core, a wire coil wound on each spool, a plate of magnetic material thru which the cores extend, a plurality of magnetic plates spaced above said first named plate, each of said cores being secured to a magnetic plate, a non-magnetic material between said magnetic plates and the first named plate, said non-magnetic material surrounding the magnetic plates and separating the same, said magnetic plates having intersecting grooves formed therein, and non-magnetic material filling said grooves whereby the plates are divided into a plurality of poles. 5

2. An electro-magnet comprising a metal base, a plurality of spaced cores secured in said base and rising therefrom, a spool on each of the cores, a wire coil wound on each of the spools, a magnetic metal plate above the spools, said cores extending thru the metal plate, a plurality of magnetic plates mounted one on top of each of the cores, a non-magnetic material separating said magnetic plates and the first named plate, each of said second magnetic plates having a pair of intersecting grooves formed therein, and non-magnetic material filling said grooves whereby each of said magnetic plates is divided into a plurality of poles. 10 15 20 25

FREDERICK SHURLEY.
